CLAIM

The ornamental design for a shower caddy, as shown and described.

DESCRIPTION

FIG. 1 is perspective view of a shower caddy showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is bottom plan view thereof.

The broken line showing of the bottles and securement suction cups is for illustrative purposes only and forms no part of the claimed design.
